UNITED STATES PATENT OFFICE.

BRUNO V. NORDBERG, OF MILWAUKEE, WISCONSIN.

PUMP AND MOTOR.

1,315,680.

Specification of Letters Patent.

Patented Sept. 9, 1919.

Application filed February 5, 1917. Serial No. 146,745.

To all whom it may concern:

Be it known that I, BRUNO V. NORDBERG, a citizen of the United States, residing at Milwaukee, in the county of Milwaukee and State of Wisconsin, have invented certain new and useful Improvements in Pumps and Motors, of which the following is a specification.

This invention relates to improvements in rotary pumps of that type in which a series of plungers or pistons are reciprocated so as to propel the fluid in a constant regular stream without any checks or momentary interruptions to its flow. It has for its object the provision of means or mechanism for imparting to the plungers or pistons the required rapid and successive reciprocation to produce the desired result.

In a general way the invention is adapted to operation in accumulator systems where it is desired to store a reserve pressure for intermittent use, such as is employed in the operation of hoisting engines, brakes, clutches, reversing gear and like appliances in which an intermittent application of power is required.

The invention is particularly adapted to pumping oil in lubricating systems and where a high pressure is desired as in fluid presses, and also for hydraulic pumping where a flow of considerable volume is required, and embodiments of the invention to these ends will be particularly described.

The invention consists in the novel construction, combination and arrangement of parts, hereinafter described, pointed out in the appended claims, and illustrated by the accompanying drawings.

In the drawings, in which similar reference characters designate corresponding parts,

Figure 1 is a perspective view showing one embodiment of the invention.

Fig. 2 is a longitudinal sectional view of the same.

Fig. 10 is a sectional view on the line $o-o$ 60 of Fig. 7.

Fig. 11 is a plan view of the face of the head.

Fig. 12 is a longitudinal sectional view of a third embodiment of the invention. 65

Fig. 13 is an enlarged plan view of the face of one of the heads.

Fig. 14 is a longitudinal sectional view through one of the arms of the pump at right angles to the section shown in Fig. 12. 70

Figs. 15, 16, 17 and 18 are detail perspective views of the component parts of one of the rotors and its adjuncts.

Figs. 19 and 20 are similar views of the wear plate and the face of one of the heads. 75

The embodiment of the invention disclosed in Figs. 1 to 6, inclusive, is particularly adapted to the pumping of oil in lubricating systems in which a comparatively light pressure is required. Referring particularly to these figures, in the integral housing 1 are journaled the two cylindrical rotors 2, of exact duplication, with their axes at right angles to each other and the circumferences of their inner ends approximately tangent to each other. Each rotor is held against longitudinal movement by the flange 3 at its outer end turning in a corresponding bearing in the housing, and by the head 4 removably secured to the housing against the outer end of the rotor. By removing the head 4 the rotor can be easily withdrawn from the housing. Extending through each rotor is a series of longitudinal bores or bearings 5 concentrically arranged around the axis of the rotor and circularly spaced equal distances a part. These longitudinal bores are preferably six in number, but the number may be varied to meet different requirements. As 80

the axes of the two rotors are at right angles to each other their longitudinal bores are also at right angles to each other.

A series of impellers 6 operate to transmit motion from one rotor to the other. Each 100 impeller comprises two arms at right angles

- to each other with one arm journaled in a bore 5 in one rotor and the other arm journaled in a corresponding bore in the other rotor. Each impeller arm has a reciprocative as well as a rotatable movement in its respective bore when the rotors are turned. One of the rotors, the horizontal one as shown in the drawings, has an integral shaft 7 axially extending from its outer end 10 through the adjacent head 4 and the stuffing-box 8 thereon. By any suitable mechanism the shaft can be driven so as to rotate its integral rotor. From the driven rotor, turned in the direction indicated by the arrow 15 in Fig. 1, rotating motion is transmitted through the impellers 6 to the other rotor. The simultaneous turning of the two rotors causes a reciprocation of the impeller arms in their respective bores so that they act as 20 pistons therein.
- In one side of the housing 1 is the induction chamber 9 into which leads the inlet pipe 10, and in the other side of the housing is the eduction chamber 11 from which 25 leads the outlet pipe 12, the two chambers being separated by the wall 13. The chamber 9 and the inlet pipe 10 constitute the induction port on one side of the device, and the chamber 11 and the outlet pipe 12 30 constitute the eduction port on the other side of the device. Through the channels 14 the induction chamber 9 communicates with the compartments 15 in the two heads 4. The compartment 15 in each head is so positioned 35 as to communicate with the outer ends or mouths of the bores 5 of the adjacent rotor while the impeller arms in such bores are moving away from the head while the rotor turns. In this movement the impeller arms 40 act as pistons to produce a suction into their bores from the compartment 15, the channel 14, the chamber 9 and the inlet pipe 10. Fluid following this passage is taken up by the buckets formed by the bores and receding 45 pistons as the mouths of the buckets pass the compartment 15.
- The eduction chamber 11, from which leads the outlet pipe 12, communicates through the channels 16 with the compartments 17 in both heads 4, the compartment 17 in each head being separated from the adjacent compartment 15 by the wall 18 passing through the axial line of the adjacent rotor. The compartment 17 in each 50 head is so positioned as to communicate with the outer ends of the bores 5 of the adjacent rotor while the impeller arms in such bores are moving toward the outer end of the rotor as the latter turns. This piston 55 movement of the arms projects any fluid contained in bores or buckets into the compartment 17. From the latter the fluid is propelled through the channel 16 into the eduction chamber 11 and is discharged 60 through the outlet pipe 12.

During the revolution of a rotor all of the impeller arms make a complete back and forth stroke in their respective bores. The relative arrangement of the rotor and the compartments 15 and 17 is such that the outer ends or mouths of the bores 5 register with the compartment 15 while the impeller arms are moving inwardly, and so that the mouths of the bores register with the compartment 17 while the impeller arms are moving outwardly. The transitory movement of the impeller arms, the changing of the direction of stroke, takes place while the mouths of the bores are passing the wall 18 between the compartments 15 and 17, the wall closing the mouths during the transitory intervals.

As the mouths of the bores or buckets successively pass the compartment 15, through the piston action of the impeller arms receding in the bores, the fluid contained in the compartment is sucked up by the buckets. As the buckets pass the outer end of the wall 18 and successively register with the compartment 17, the impeller arms having changed the direction of their stroke from suction to propulsion as the bores pass the wall, the fluid carried by the buckets is projected by the return piston action of the arms into the compartment 17, from which the fluid is forced through the channel 16 into the eduction chamber 11 and discharged through the outlet pipe 12. When the buckets or mouths of the bores pass the inner end of the wall 18 the impeller arms again change the direction of their stroke from propulsion to suction, thereby completing the cycle of operations.

As each impeller arm and its bore constitute a pump, and as the induction port successively communicates with such pumps of both rotors during the suction action of the pumps, and as the eduction port successively communicates with the pumps during their propulsion action, and as the rotors are driven at a very high rate of speed, one thousand rotations a minute in actual practice, the fluid passes through the device with a constant rapid flow having a volume depending upon the size of the machine.

While the device has been described as one for propelling fluids, yet it can be readily operated as a motor. Fluid under pressure entering the induction port and impinging on the ends of the impeller arms will reciprocate the latter and cause a rotation of the rotors.

The embodiment of the invention illustrated by Figs. 7 to 11, inclusive, is particularly designed to operate against high pressure, such as in pumping oil for compression machines. In this construction the housing 21 is divided longitudinally in the plane of the section shown in Fig. 7, instead of being made of a single piece of metal as in the

70

130

former embodiment. The purpose of dividing the housing is to permit of more readily assembling the parts. Journaled in the housing 21 are the cylindrical rotors 22 with 5 their axes at right angles to each other and provided with longitudinal bores 23 in which are journaled the arms of the impellers 24.

The outer end of the body part of each 10 rotor 22 is conically shaped and is journaled in a concave bearing in the adjacent head 25. Integral with and projecting from the outer end rotor is the spindle 26 extending through the head 25. At the inner end of the spindle 15 is the bearing 27 journaled in the adjacent head and extending beyond the latter. On the projecting end of the bearing 27 is the loose collar 28 held in place against the head by the nut 29 turned onto the spindle. By 20 adjusting the nut the longitudinal play of the rotor can be regulated. The outer end of the spindle 26 is journaled in the cap 30 secured in the outer end of the annular flange 31 projecting from the head 25. On the 25 outer end of the spindle 26 of the horizontal rotor is the pulley 32 to receive a belt for driving the rotors, motion being transmitted from the driven rotor to the other one by the impellers.

In opposite sides of the housing 21 are the 30 induction and eduction ports 33 and 34, respectively. Through the channels 35 the induction port communicates with the compartments 36 in the heads 25 adjacent to the outer ends of the rotors. Each compartment 35 communicates with the outer ends of the bores 23 of the adjacent rotor while the impeller arms in such bores are moving inwardly to produce a suction into the compartment from the induction port 33 and channel 35. Through the channels 37 the eduction port 34 communicates with the compartments 38 in the heads 25 adjacent to the outer ends of the rotors. axes of their respective rotors and pass through the inclined faces of the conical bearings at the inner ends of the rotors. By so positioning the mouths or bucket openings of the bores they can be given a greater cross-area than in the first embodiment, which permits the fluid to flow more easily between the compartments and the bores. The conical bearing at the inner end of each rotor also permits the use of longer impeller arms, as compared with those in the first embodiment. The use of the longer impeller arms is an advantage where the pump is acting against high pressure, for the arms having longer bearings in their respective bores during their reciprocation and rotation therein have less tendency to bind than they would have with shorter bearings. (It is to be noted that Fig. 7, showing the second embodiment of the invention, is made on a much smaller scale than Fig. 2 showing the first embodiment.)

The use of the conical bearings between the inner end of the rotor and the adjacent head, together with the extended bearing 27, the loose collar 28 and the nut 29, facilitate the lubrication of the wearing parts of the rotor. Some of the oil that is being pumped is forced by the propelling movement of the impeller arms from the compartment 38 between the conical bearings at the inner end of the rotor and the adjacent head. In the preliminary adjustment of the parts the nut 29 is first set tightly against the collar 28 to clamp the latter against the bearing 27, then it is slightly turned back to permit a slight separation of the different bearing surfaces. This separation permits the oil to pass from the compartment 38 into the space formed by the separation to form a film between the different bearing surfaces. In this way a thorough lubrication of the bearing surfaces of the rotor is obtained.

In this third embodiment the housing 40 is divided longitudinally to facilitate the assembling and mounting of the different parts as in the second embodiment. In this housing are journaled the rotors 41 with their axes at right angles to each other. Through each rotor parallel to its axis pass the bores 42 in which are journaled the reciprocative arms of the impellers 43. Each of the rotors has a shaft or spindle 44 passing through the rotor, the rotor being clamped between the nut 45 and washer on the inner end of the shaft and the shoulder 46 at the outer end of the shaft. The outer end of the shaft is journaled in the head 47 secured to the casing against the outer end of the rotor. To prevent leakage through the

it is to be observed that the mouths or openings of the bores 23 into the compartments 36 and 38 are at an obtuse angle to the

head a packing 48 is compressed around the shaft between the nut 49 and the plate 50 seated in an annular recess in the head. One of the shafts is continued beyond the head, as at 51, to receive rotary power. Motion imparted to this shaft drives the rotor attached to it, and through the impellers 43 the other rotor is driven, and the rotation of the two rotors causes the reciprocation of the impeller arms in their bores.

In each head 47 is an induction port 52 and an eduction port 53. Each port is so shaped as to produce an acceleration of fluid as it enters the pump and a retardation when it leaves the pump, so as to gradually change in the induction port the low velocity in the inlet pipe into a higher velocity corresponding to the piston speed of the impeller arms, and so as to change in the eduction port the comparatively high velocity of the piston speed to the required lower speed of the discharge pipe.

On one side of the partition 54 the induction port 52 communicates with the mouths of the bores 42 as the impeller arms in such bores are moving inwardly to produce a suction so that the bores will take up the fluid, and on the other side of the partition 54 the eduction port 53 communicates with the mouths of the bores as the impeller arms are moving outwardly therein to produce a propulsion of the fluid contained in the bores through the eduction port. The impeller arms change the direction of their stroke as they pass over the partition 54.

In the housing 40 over the inner ends of the rotors 41 and the angles of the impellers 43 is the closed chamber 55 to contain a suitable lubricant. In this chamber a pressure is maintained by a suitable auxiliary pump slightly higher than the pressure of the fluid passing through the main pump so as to force the lubricant between the bearings of the impeller arms and of the rotors against the action of the propelled fluid.

Each rotor 41 is journaled in a bushing 56 of non-corrodible material removably mounted in the housing 40. On the outer end of the bushing is the flange 57 turnable in a corresponding groove in the adjacent wall of the housing, the flange serving to hold the bushing against longitudinal movement. Between the flange 57 and the flange 58 on the outer end of the rotor are the packing rings 59 around the rotor. The packing rings are clamped against the flange 57 by the follower 60 secured to the housing by screws 61. The packing rings prevent leakage from between the outer ends of the rotor and bushing of the lubricant forced from the chamber 55 between the inner ends of the rotor and bushing.

In the rotation of each rotor 41 the greatest wear takes place between its outer face

and the opposing head 47. Between these wearing surfaces a lubricant cannot be introduced very well as it might contaminate the water as the latter passes from the induction port to the rotor bores, or from the latter to the eduction port. On the outer face of the rotor is removably secured the wear plate 62 having openings 63 to register with the mouths of the bores 42. Set in the opposing face of the head 47 is the annular plate 64 removably secured in place, and inside of the annular plate is seated the cross-plate 65, removably secured to the partition 54. On opposite sides of this cross-plate and inside of the annular plate 64 the induction and eduction ports 52 and 53, respectively, communicate with the mouths of the bores 42. The plates 62, 64 and 65 are formed of non-corrodible material so as to be unaffected by any chemicals that the passing water might contain, and as they are removable they can be readily replaced when worn.

While I have shown in the various forms or embodiments of my invention the impellers extending at right angles to each other, it is of course conceivable that they can be placed at any other angle greater than 90° and short of 180°. By the employment of the impellers at 90° from each other I attain the longest stroke possible, though where the angle is over 90° a somewhat easier drive may be attained with a consequent reduction of stroke. In every instance, however, the axes of the bores into which the impellers extend would of course lie parallel to the axis of the rotor, and the axes of the two rotors would have the same angular relationship to each other as the angular relation of the two elements of the impeller.

What I claim, is:

1. In a device of the character described, a housing having induction and eduction ports, a cross partition forming induction and eduction chambers communicating respectively with said ports, cylindrical rotors journaled in the housing with their axes at right angles to each other and each rotor having a bore parallel with its axis and being so mounted that the mouth of its bore alternately passes from one side to the other of said partition and communicates alternately with the induction and eduction chambers as such rotor turns, and an impeller having arms at right angles to each other with an arm journaled in the bore of each rotor, said impeller operating to transmit motion between the rotors as one of them is driven and the arms of the impeller reciprocating in the rotor bore that communicates with the chambers so as to produce in the bore a suction when its mouth communicates with the induction chamber and to produce a propulsion when the mouth of the

bore communicates with the eduction chamber.

2. In a device of the character described, a housing having induction and eduction ports, a cross partition forming induction and eduction chambers communicating respectively with said ports, cylindrical rotors journaled in the housing with their axes at right angles to each other and each rotor having a bore parallel with its axis and the rotors being so mounted that the mouths of their bores pass from one to the other side of the partition and successively communicate with the induction and eduction chambers as the rotors turn, and an impeller having arms at right angles to each other with an arm journaled in the bore of each rotor, said impeller operating to transmit motion between the rotors as one of them is driven and the arms of the impellers reciprocating in their respective bores to produce in each bore a suction when its mouth communicates with the induction chamber and to produce in each bore a propulsion when its mouth communicates with the eduction chamber.

3. In a device of the character described, a housing having induction and eduction ports, a cross partition therein forming induction and eduction chambers, cylindrical rotors journaled in the housing with their axes at right angles to each other and each rotor having a plurality of bores parallel with its axis and the rotors so mounted that the mouths of their bores successively communicate with the induction and eduction chambers as the rotors turn, and a plurality of impellers with each having arms at right angles to each other journaled in the bores of the rotors, said impellers operating to transmit motion between the rotors as one of the rotors is driven and the arms of the impellers reciprocating in their respective bores so as to produce in each bore a suction when its mouth communicates with the induction chamber and to produce a propulsion in each bore when its mouth communicates with the eduction chamber.

4. In a device of the character described, a housing having induction and eduction chambers provided with ports leading to the exterior of the housing, duplicate cylindrical rotors journaled in the housing with their axes at right angles to each other and each rotor having a plurality of bores parallel with its axis, a plurality of impellers with each having arms at right angles to each other journaled in the bores of the duplicate rotors, said impellers operating to transmit motion from one rotor to the other as either rotor is driven, the arms of the impellers reciprocating in their respective bores to produce suction and propulsion in the outer ends of the bores, a head secured to the housing over the outer end of each rotor, each head having a compartment communicating

with the induction chamber in the housing and registering with the outer ends of the bores as suction is produced in the latter, and each head having a second compartment communicating with the eduction chamber in the housing and registering with the outer ends of the bores as propulsion is produced therein.

5. In a device of the character described, a pumping mechanism comprising a housing with induction and eduction ports, a rotatable cylindrical rotor journaled in the housing having a conical bearing at one end and said rotor having a plurality of bores parallel with its axis with the mouths of the bores leading through the conical bearing of the rotor and operating to communicate successively with the induction and eduction ports, and reciprocating piston arms in the bores operating to produce suction through the mouths of the bores as such mouths communicate with the induction port and said arms operating to produce propulsion through the mouths of the bores as such mouths communicate with the eduction port.

6. In a device of the character described, a pumping mechanism comprising a housing with induction and eduction ports, a rotatable cylindrical rotor journaled in the housing having a conical bearing at one end and said rotor having a plurality of bores parallel with its axis with the mouths of said bores leading through the conical bearing and operating to communicate successively with the induction and eduction ports, a head secured to the housing with a concave bearing to register with the conical bearing of the rotor, an axial spindle projecting from the conical bearing end of the rotor through the head, a collar on the spindle outside of the head, a nut on the spindle outside of the collar to regulate the space between the conical bearing of the rotor and the concave bearing of the head, and reciprocating piston arms in the bores of the rotor operating to produce suction through the mouths of the bores as such mouths communicate with the induction port and said arms operating to produce propulsion through the mouths of the bores as such mouths communicate with the eduction port.

7. In a device of the character described, a pumping mechanism comprising a housing with induction and eduction ports, a rotatable cylindrical rotor journaled in the housing having a conical bearing at one end and said rotor having a plurality of bores parallel with its axis with the mouths of said bores leading through the conical bearing, a head secured to the housing with a concave bearing to register with the conical bearing of the rotor, an axial spindle projecting from the conical bearing end of the rotor through the head, a collar on the

- spindle outside the head, a nut on the spindle to clamp the collar against the head to regulate the play between the surfaces of the conical bearing of the rotor and the 5 concave bearing of the head, reciprocating piston arms in the bores of the rotor to produce alternately suction and propulsion through the mouths of the bores, and said head having a compartment communicating 10 with the induction port and also registering through the concave bearing of the head with the mouths of the bores as suction is produced in the latter, and said head also having a second compartment communicating 15 through the concave bearing of the head with the eduction port and registering with the mouths of the bores as propulsion is produced in the latter.
8. In a device of the character described, 20 a pumping mechanism comprising a housing with induction and eduction ports, a rotatable cylindrical rotor journaled in the housing having at one end a conical bearing turning in an opposite concave bearing 25 and said rotor having a plurality of bores parallel with its axis with the mouths of said bores leading through the conical

bearing and operating to communicate successively with the induction and eduction ports, piston arms reciprocating in the bores 30 of the rotor to produce suction in the mouths of the bores as the latter communicate with the induction port and to produce propulsion in the mouths as the latter communicate with the eduction port, and means 35 for axially adjusting the rotor to regulate the space between the conical and concave bearings.

9. In a device of the character described, a housing having induction and eduction 40 ports and intermediate channels, a pair of rotors with axes at an angle to each other and provided with longitudinal bores, means for driving one of said rotors and impellers having arms reciprocating in the 45 bores operating as pistons to propel fluid through the intermediate channels from the induction to the eduction ports, said impellers also operating to transmit rotary motion from the driven rotor to the other. 50

In testimony whereof I have signed my name to this specification.

BRUNO V. NORDBERG.
